CONTAINER FOR TOILETRIES OR THE LIKE

Leonard Lewis and Lester Richter, Brooklyn, N. Y.

Application November 13, 1952, Serial No. 22,268

Term of patent 3½ years

(Cl. D58—9)

To all whom it may concern:

Be it known that we, Leonard Lewis and Lester Richter, both citizens of the United States, both residing at Brooklyn, New York, in the county of Kings and State of New York, have invented a new, original, and ornamental Design for a Container for Toiletries or the like, of which the following is a specification, reference being had to the accompanying drawing, forming part thereof.

In the drawing:

Fig. 1 is a front perspective view of a container for toiletries or the like, showing our new design;

Fig. 2 is a top plan view of the same; and

Fig. 3 is a vertical sectional view of the same taken on the line 3—3 of Fig. 2.

The dominant feature of our design resides in the portions shown in full lines.

We claim:

The ornamental design for a container for toiletries or the like, as shown and described.

LEONARD LEWIS.

LESTER RICHTER.
